UNITED STATES PATENT OFFICE.

C FRANK HAWKINS, OF BREESPORT, NEW YORK.

DESIGN FOR A BOTTOM FOR CREAM-SEPARATORS.

SPECIFICATION forming part of Design No. 30,962, dated June 6, 1899.

Application filed May 5, 1899. Serial No. 715,744. Term of patent 7 years.

To all whom it may concern:

Be it known that I, C FRANK HAWKINS, a citizen of the United States, residing at Breesport, in the county of Chemung and State of

5 New York, have invented and produced a new and original Design for Bottoms for Cream-Separators, of which the following is a specification, reference being had to the accompanying drawings, forming part thereof.

10 Figure 1 is a side elevation of the bottom, showing my new design; Fig. 2, a plan view of the same, and Fig. 3 a front elevation.

As shown in the drawings, the leading or material feature of my design consists of an 15 inverted cone A, with a radial groove or cor-

rugation B leading out from the apex of the cone to the periphery, the bottom of the groove or corrugation being parallel with the baseline of the cone.

Having described my invention, what I claim as new, and desire to secure by Letters Patent, is—

The design for a bottom for cream-separators as herein shown and described.

In testimony whereof I have affixed my signature in presence of two witnesses.

C FRANK HAWKINS.

Witnesses:

C. TRACEY STAGG,
A. S. DIVEN.
